(57) **CLAIM**

The ornamental design for a pillow holder, as shown and described.

DESCRIPTION

FIG. 1 is a top, front, right perspective view of a pillow holder showing my new design;

FIG. 2 is a bottom, rear, left perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the pillow holder that form no part of the claimed design. Purpose of this design: It is used to place or hold mobile phone, tablet computer and other objects. Meanwhile, the groove in the middle part can place objects. The base is a soft bad like throw pillow.
